ELECTRICAL CONTROL CIRCUIT AND
DEVICE THEREFOR

John H. Wheelock, Fitzwilliam, N. H., assignor
to Signal Engineering & Manufacturing Company, New York, N. Y., a corporation of Massachusetts

Application November 24, 1937, Serial No. 176,307

9 Claims. (Cl. 175—375)

The present invention relates to electrical control circuits and devices, and relates particularly to an improved arrangement for controlling the operation of electrical apparatus having a relatively heavy current consumption, by means of control devices working in a circuit in which the current consumption is reduced to a minimum.

The circuit and devices of the present invention are particularly adapted for use in connection with control apparatus employing extremely sensitive electrical contacts of low current carrying capacity. For example, relatively slight movements of a thermo-responsive element may be employed, in accordance with the invention, to perform desired functions through making or breaking an electrical circuit, with complete elimination of arcing at the thermo-responsive element itself, since all control circuits carrying any appreciable current are broken at points entirely removed from the element. The above and other advantageous features of the invention will hereinafter more fully appear from the following description considered in connection with the accompanying drawing in which:

Fig. 1 is a schematic view of a control circuit and devices embodying the invention.

Fig. 2 is a schematic view of the apparatus of Fig. 1, illustrating a different operating condition.

Fig. 3 is a view in side elevation of the control device shown in Fig. 1.

Fig. 4 is a view in front elevation of the device in Fig. 3, with some parts broken away to show the construction.

Like reference characters refer to like parts in the different figures.

Referring first to Figs. 1 and 3, there will first be described an illustrative embodiment of a device for performing certain essential functions in the control circuit of the present invention, although it will be readily understood that the control device itself is susceptible of many structural modifications without departing from the invention. The control device generally comprises a magnetic core 1 of U-shaped form one leg of which is surrounded by a winding 2. The other core leg provides a pivot 3 for an armature 4 and full energization of the winding 2 is adapted to turn the armature 4 from the position of Fig. 1 to the position of Fig. 2.

A latch 5 pivoted at 6 is associated with the free end of the armature 4 the upper end of the latch providing a notch 7 in which the free end of the armature 4 rests when in the de-

energized position of Fig. 1. The latch 5 provides an extension 8 overhanging the pivot 6 to such an extent that when the armature 4 is raised due to full energization of the winding 2, the entire latch turns in a counterclockwise direction to engage a second notch 9 with the end of the armature 4. Hence, subsequent deenergization of the winding 2, with the latch in the position of Fig. 2, has no effect on the armature 4 which remains latched in its raised position.

The overhanging portion 8 of the latch 5 is associated with a solenoid or trip coil 10 having a magnetic plunger 11 movable therein. With the trip coil 10 in its normal deenergized condition the plunger 11 rests against a stop 12 with only a portion of the plunger within the trip coil, so that energization of the coil 10 will draw the plunger 11 upwardly in the direction of the latch portion 8.

The core 1 also carries an auxiliary armature 13 pivoted at 1a, the armature 13 overhanging the winding 2 and terminating in a beveled edge 13a that is parallel to a beveled edge 14a on an extension 14 of the core leg carrying the winding 2. The armature 13 provides a weighted extension 15 beyond the pivot 1a so that normally, with the winding 2 in deenergized condition, the downwardly extending portion of the armature 13 is tilted slightly away from the core extension 14 with an appreciable air gap between the beveled surfaces 13a and 14a. As will readily appear from consideration of Fig. 3, the gap between the surfaces 13a and 14a is considerably less than the normal air gap between the armature 4 and the core leg when the device is deenergized, and since the armature 13 is extremely light in weight and nearly in a condition of balance about its pivot 1a, a relatively small degree of energization of the winding 2 (insufficient to have any effect on the main armature 4), will however attract the armature 13 and move it into a vertical position, as indicated in dotted lines in Fig. 1.

The free end of the armature extension 15 provides an insulating tip 15a which is normally lightly in engagement with one of a pair of spaced contacts 16, so that attraction of the armature 13 will cause these contacts 16 to close, as indicated in dotted lines. The latch 5 provides a projecting insulating tip 5a, and with the latch 5 in its non-locking position with respect to the armature 4, the tip 5a maintains a pair of contacts 17 in engagement. Therefore, with the control device in deenergized condition, the contacts 16, controlled by the auxiliary armature 13, are open while the contacts 17 controlled by the latch 5

5 are closed, and the function of these contacts in the control circuit will shortly appear.

The armature 4 carries a cross bar 13 which, as best shown in Fig. 4, carries an arm 19 insulated from the bar 13 at 20. The free end of the arm 19 carries a pair of contacts 21 connected by a bridging member 22 and when the armature 4 is raised, as shown in Fig. 2, the contacts 21 establish a circuit between a pair of spaced contacts 23. The armature also carries an arm 24 insulated from the bar 13 and contacts 25 at the end of the arm 24 are connected by a bridging member 26. These contacts 25 establish a circuit between spaced contacts 27 when the armature 4 is raised, as shown in Fig. 2, and for the purpose of simplifying the wiring connections of the circuit of Fig. 1, the arm 24 is shown as extending at right angles to the arm 19.

As previously pointed out, the object of the invention is to provide for the control of the operation of apparatus having a relatively heavy current consumption, with the duration of the flow of current through the control circuit itself reduced to a minimum and arcing at the movable actuating elements entirely eliminated. As an illustrative embodiment of the utility of the invention, there is shown in Figs. 1 and 2 its functioning in connection with the control of the operation of an electrical motor M by the limited movement of the very sensitive thermo-responsive element T. For example, the element T may be part of a thermostat of the character frequently employed in connection with the temperature control of buildings, while the motor may be of the type employed to supply a liquid fuel burner. Generally in such a system, it is required that the motor shall be operated when the temperature falls below a certain predetermined minimum and shall be disconnected when the temperature reaches a predetermined maximum in response to functioning of the heating system.

For the purpose of obtaining the above described results, one terminal of the motor M is connected to a supply main 28 while the other terminal is connected to one of the spaced contacts 23. The other contact 23 is connected to a supply main 29 so that the closure of the contacts 23 by the contacts 21 and bridging member 22 will cause the motor to operate as long as the armature 4 remains in the position of Fig. 2. The thermo-responsive element T is shown diagrammatically as being of the type having one end anchored, with a free end adapted to move in opposite directions in accordance with its heating and cooling upon an increase or decrease of temperature. As shown, cooling of the element T causes its free end to move towards a stationary contact 30 connected to one of the normally closed contacts 17, while heating of the element T will cause its free end to engage a stationary contact 31 connected to one terminal of the trip coil 10. The fixed end of the element T is connected through a current limiting resistor 32 to the supply main 28.

In considering the operation of the control circuit and devices, let it be assumed that the element T is cooling by reason of being subjected to a decrease in temperature. The free end of the element T is, therefore, moving towards the right, as indicated by the small arrow in Fig. 1, and when it engages the contact 30, a circuit is established to the winding 2 from the supply main 28 through the resistor 32, element T, contact 30 and normally closed contacts 17. This re-

sults in a current flow which is not sufficient to harm the relatively delicate thermostatic contacts T and 30, nor is it sufficient to attract the armature 4; although it will cause the auxiliary armature 13 to be attracted and close the contacts 16, as indicated in dotted lines in Fig. 1. When this occurs, a circuit is established from the supply main 28 through closed contacts 16 to the closed latch contacts 17 and one terminal of the winding 2, and since the other terminal is connected to supply main 29, there results full energization of the winding 2, the resistor 32 and thermostatic contacts T and 30 then being shunted out through contacts 16.

The armature 4 thereupon pulls up, as shown in Fig. 2, and as the free end of the armature leaves the notch 7 on the latch 5, the latter turns about its pivot 6 into a substantially vertical position with the upper notch 9 receiving the end of the armature. Closure of the armature 4 and functioning of the latch 5 bring about a number of changes in the control circuits which will be described in the order of their occurrence. In the first place, closure of the motor contacts 23 by the bridging contacts 21, as the armature pulls up, starts the motor M and the motor will continue to operate directly across the mains 28 and 29 as long as the armature 4 remains locked up. However, the winding 2 is completely deenergized almost immediately after the armature 4 pulls up due to the fact that as the latch 5 drops to the armature locking position, the contacts 17 are opened by upward movement of the tip 5a, thereby breaking the circuit of the winding 2 even though at that moment the contacts 16 are still closed by reason of the attraction of the auxiliary armature 13. The control circuit is, therefore, in the condition of Fig. 2 almost immediately after the armature 4 is locked up by the latch 5 and obviously when the element T starts to move towards the left in response to a rise in temperature due to continued operation of the motor M, there can be no arcing at the contact 30 due to the fact that the circuit originally established from the main 28 through the contact 30 has previously been broken by opening of the latch contacts 17.

Locking up of the armature 4 also accomplishes another result, namely, the closure of a portion of the circuit of the trip coil 10 in advance of completion of that circuit when the thermo-responsive element T engages the contact 31. As previously pointed out, the arm 24 on the armature 4 carries bridging contacts 25 and these contacts establish a circuit between the stationary contacts 27 when the armature is locked up, thereby connecting the upper terminal of the trip coil 10 to the supply main 29. Therefore, when continued movement of the free end of the element T to the left, due to its heating, results in engagement with the contact 31, a circuit is established through the trip coil 10, due to the previous closure of the contacts 27. Trip coil 10 is so designed that the current flow through this circuit is of the same order as that through the contact 30, and the resulting upward movement of the plunger engages the latch extension 8 and turns it about its pivot to the dotted line position of Fig. 2.

Upon release of the free end of the armature 4 from the upper notch 9, the armature 4 drops to the full line position of Fig. 1, thereby immediately stopping the motor M due to the opening of contacts 23. At the same time opening of contacts 27 through movement of the arm 24

deenergizes the trip coil 10, so that the plunger 11 returns to its deenergized position. However, the latch 5 cannot fall back owing to the fact that the free end of the armature 4 is then received in the lower notch 1, thereby leaving the latch in an unbalanced condition ready to perform its function of latching up the armature upon the next full energization of the winding 2. Obviously, opening of the contacts 27 in circuit with the trip coil 10 eliminates any possibility of arcing at the contact 31, when the element T in response to a decreasing temperature, following stoppage of the motor M, starts to move to the right and leave the contact 31.

15 The above described cycle of operation will continue indefinitely in response to temperature changes to which the element T is subjected without any possibility of injurious arcing ever occurring between the sensitive contacts 30 and 31 and the element T itself. This is a most important feature of the invention since it is well known that many thermostatic devices fail to function properly after being in service for any considerable time due to deterioration of electrical contacts in the device itself by arcing. Furthermore, it is to be noted that the main winding 2 and the trip coil 10 are only momentarily energized in response to the functioning of the non-arcing element T. When sufficient current is passed through the winding 2 to cause the armature 4 to pull up, the circuit is almost immediately broken at the latch controlled contacts 11, while the trip coil circuit is broken immediately after release of the latch unlocks the armature 4 and opens the contacts 27. Therefore, even though relatively long periods of time may elapse between engagement of the element T with the contacts 30 and 31, no part of the control circuit and associated devices is being traversed by a continuously maintained current. This reduces the current consumption of the control circuit and associated devices to an absolute minimum, thereby greatly increasing the reliability of the control arrangement as a whole.

45 I claim:

1. In an electrical control circuit, a source of electrical energy, a current consuming device having one terminal thereof connected to one side of said source, a control element having one terminal thereof connected to the other side of said source and movable to complete a circuit through said current consuming device, means in circuit with said element for restricting the flow of current through said device to a low initial value, means responsive to energization of said device at said initial current value for increasing the flow of current through said device, independently of said element, and means responsive to the increased current flow through said device alone, to interrupt the flow of current through said element.

2. In an electrical control circuit, a source of electrical energy, a current consuming device having one terminal thereof connected to one side of said source, a control element having one terminal thereof connected to the other side of said source and movable to complete a circuit through said current consuming device, means in circuit with said element for restricting the flow of current through said device to a low initial value, means responsive to energization of said device at said initial current value for increasing the flow of current through said device and means responsive to the increased current flow through said device alone to automatically interrupt the

flow of current through said device and said control element while the latter remains stationary.

3. In an electrical control circuit, a source of electrical energy, an operating winding having one terminal thereof connected to said source, a control element having one terminal thereof connected to the other side of said source and movable to complete a circuit through said winding, means in circuit with said element for restricting the flow of current through said winding to a low value, means responsive to the initial energization of said winding through said element, and controlled by said winding, to increase the flow of current through said winding independently of said element, and means responsive to the increased energization of said winding alone to interrupt automatically the flow of current through said element.

4. In an electrical control circuit, a source of electrical energy, an operating winding having one terminal thereof connected to said source, a control element having one terminal thereof connected to the other side of said source and movable to complete a circuit through said winding, means in circuit with said element for restricting the flow of current through said winding to a low value, means responsive to the initial energization of said winding through said element, and controlled by said winding, to increase the flow of current through said winding independently of said element, and means responsive to the increased energization of said winding alone to interrupt automatically the flow of current through said winding and said control element while the latter remains stationary.

5. In an electrical control circuit, a source of electrical energy, a circuit controlling device comprising a winding, having one terminal connected to said source, a control element having one terminal thereof connected to the other side of said source, a stationary contact engageable by movement of said element and connected to the other terminal of said winding, engagement of said element with said contact serving to cause initial energization of said winding at a low current value, means for causing increased energization of said winding, independently of said control element, and means responsive to increased energization of said winding to interrupt the flow of current through said element and contact.

6. In an electrical control circuit, a source of electrical energy, a circuit controlling device comprising a winding having one terminal connected to said source, a control element having one terminal thereof connected to one side of said source, a stationary contact engageable by said element for completing the circuit through said winding, current limiting means for restricting the flow of current through said element and winding to a small initial value, means controlled by the initial current flow through said winding for increasing the current through said winding alone and means responsive to increased energization of said winding to interrupt the flow of current through both said element and said winding, while said control element remains in engagement with said contact.

7. In an electrical control circuit, a source of electrical energy, a circuit controlling device comprising a winding having one terminal thereof connected to one side of said source, a magnetic member responsive to energization of said winding at a given current value, a control element having one terminal thereof connected to the other side of said source and movable to com-

plete a circuit through said winding to energize the same at a current value lower than said first-named current value, means responsive to initial energization of said winding at the lower current

5 value to increase the current flow therethrough and cause it to attract said magnetic member, means responsive to attraction of said magnetic member to break the circuit between said control element and said winding, while said element remains stationary, and means to maintain said magnetic member in its attracted position, after the flow of current through said winding has been interrupted.

8. In an electrical control circuit, a source of 15 electrical energy, a winding having one terminal thereof connected to one side of said source, a second winding normally having both terminals unconnected to said source, a movable control element having one terminal thereof connected 20 to the other side of said source and a pair of stationary contacts engageable by said element, with each contact connected to a terminal of one of said windings, movement of said element in one direction to engage one contact serving to cause 25 initial energization of the first-named winding through connection of its other terminal to said source through said element, and means responsive to initial energization of said source-connected winding to automatically interrupt the 30 flow of current from said element-engaged contact to said winding and to connect one terminal

of said second-named winding to said source, in advance of engagement of said element with said other stationary contact.

9. In an electrical control circuit, a source of 5 electrical energy, a winding having one terminal thereof connected to one side of said source, a second winding normally having both terminals unconnected to said source, a movable control element having one terminal thereof connected to the other side of said source and a pair of stationary contacts engageable by said element, with each contact connected to a terminal of one of said windings, movement of said element in one direction to engage one contact serving to cause 10 initial energization of the first-named winding through connection of its other terminal to said source through said element, and means responsive to initial energization of said source-connected winding to automatically interrupt the 15 flow of current from said element-engaged contact to said winding and to connect one terminal of said second-named winding to said source, with further movement of said element in the opposite direction to engage the other of said contacts serving to energize the second-named 20 winding, and means responsive to energization of said second-named winding for restoring the previously broken circuit between said first-named winding and said contact.

30 JOHN H. WHEELOCK.
